US0D1059708S

(12) **United States Design Patent** (10) **Patent No.:** **US D1,059,708 S**
(45) **Date of Patent:** **** Jan. 28, 2025**

(54) **VACUUM CLEANER PART**

(71) Applicant: **Dyson Technology Limited**, Wiltshire (GB)

(72) Inventors: **Davide Leoni**, Bristol (GB); **David Christopher James Newton**, Bristol (GB); **Stephen Robert Dimbylow**, Swindon (GB)

(73) Assignee: **Dyson Technology Limited**, Malmesbury (GB)

(**) Term: **15 Years**

(21) Appl. No.: **29/835,484**

(22) Filed: **Apr. 19, 2022**

(30) **Foreign Application Priority Data**

Oct. 26, 2021 (EM) 008736409-0006
(51) **LOC (15) Cl.** **15-05**
(52) **U.S. Cl.** **D32/25**
(58) **Field of Classification Search**
USPC D32/1, 4-25, 28-35, 38-40, 45

(57) **CLAIM**

The ornamental design for a vacuum cleaner part, as shown and described.

DESCRIPTION

FIG. 1 is a perspective view of a vacuum cleaner part, illustrating our new design;

FIG. 2 is a first side view thereof;

FIG. 3 is a second side view thereof;

FIG. 4 is a front view thereof;

FIG. 5 is a third side view thereof;

FIG. 6 is a fourth side view thereof; and,

FIG. 7 is a rear view thereof.

The broken lines showing portions of the vacuum cleaner part in the drawings form no part of the claimed design.

1 Claim, 7 Drawing Sheets
